NECKTIE

Samuel Klaus, Brooklyn, N. Y.

Application October 23, 1956, Serial No. 43,492

Term of patent 7 years

(Cl. D3—16)

Fig. 1 is a perspective view of a necktie showing my new design.

Fig. 2 is a sectional view thereof taken on line 2—2 of Fig. 1.

The wavy lines ornamentation shown in Fig. 1 extend around the necktie and the undisclosed face of the tie is plain and unornamented.

I claim:

The ornamental design for a necktie, as shown and described.
